UNITED STATES PATENT OFFICE

VICTOR F. HAMMEL, OF NEW YORK, N. Y.

CYLINDRICAL STRUCTURE

Application filed October 6, 1928. Serial No. 310,889.

This invention relates to cylindrical structures having great stiffness and strength, and which may be easily and quickly made.

One object of this invention is to produce an integral cylindrical net-work which includes trussed longitudinal structural members to provide a unit structure having great stiffness, this being attained by permitting the longitudinal members to act under strain as compression struts.

A second object of this invention is to employ rods, or bars, or both, disposed lengthwise of and connecting the longitudinal structural members and said rods, or bars, in the desired net-work relation.

A third object of this invention is to produce such a structure having the longitudinal structural members in a circular or other group, and with the rods, or bars, disposed helically lengthwise of the members and connecting the longitudinal members and the bars or rods in the mentioned net-work relation.

A fourth specific object of this invention is to produce such a structure wherein the rods, or bars, are woven or otherwise helically arranged around and connected to a circular or other group of spaced longitudinal structural members.

A fifth object of this invention is to produce a structure like that just before-mentioned, in which some of the rods or bars are helically arranged clockwise around the group of longitudinals and in which structure other rods, or bars, are helically arranged anticlockwise around said group of longitudinals.

A sixth object of this invention is to produce a structure, having any or all of the characteristic features noted, and formed of sections connected end to end to form a long post.

A seventh object of this invention is to produce a structure having any or all of the characteristic features noted, and also having additional stiffening means or devices carried thereby at desired intervals.

An eighth object of this invention is to produce a structure having any or all of the characteristic features noted and wherein some of

the longitudinal structural members extend throughout the entire length of the structure, while the remainder of the longitudinal structural members extends for only a portion of the length of the structure.

A ninth object of this invention is to provide a method having simple steps for speedily assembling the elements ((a) the longitudinal structural members and (b) the rods, or bars) and connecting the same in the predetermined net-work relation.

A tenth object of this invention is to provide mechanism, preferably for practicing the method mentioned, for speedily assembling and connecting the elements of the structure.

A further object of the invention is to provide post or pole having a greater resistance against movement when set or embedded in the ground, than a solid or tubular pole of the same external dimensions.

Other objects of this invention will be mentioned hereinafter and in the appended claims.

Referring to the accompanying drawings, Fig. 1 illustrates a cross-section of a grooved mandrel, being a support for holding a plurality of longitudinal structural members in the preferred spaced side-by-side relation. Fig. 2 is a side elevational view of a portion of such a mandrel.

Fig. 3 is a cross-sectional view of the mandrel of Fig. 1, with longitudinal structural V-shaped angles fitted in the grooves of the mandrel. Fig. 4 is a side elevational view of a portion of the mandrel and of the longitudinals fitted in the grooves of such mandrel.

Fig. 5 is a cross-sectional view of the mandrel before-mentioned and of the longitudinals within the grooves thereof, and also showing the near-by winding or laying devices for winding or laying rods, or bars, around the held longitudinals, together with near-by electrical or other welding devices for welding the wound or laid rods to the longitudinals. Fig. 6 is a side elevational view of the parts illustrated in Fig. 5.

Figs. 1—2, 3—4 and 5—6 illustrate the principal steps of my new method for as-

sembling and connecting the elements of one form of my new cylindrical structure.

Fig. 7 is a side elevational view of one form of my new cylindrical structure, being 5 a pole shown as set in the ground and formed of successive sections connected end to end. The rods, or bars, are shown as helically disposed around the pole in both clockwise and anti-clockwise directions.

10 Fig. 8 illustrates, in plan view, an arrangement of parts wherein the longitudinal structural members are outside of the pole or post and the helically or otherwise disposed rods, or bars, are inside of and connected to the 15 grouped longitudinals. Fig. 9 is a side elevational view of a portion of the resulting pole.

Fig. 10 is a plan view, quite like that of Fig. 8, showing rods, or bars arranged outside as well as inside of and connected with the longitudinals. Fig. 11 is a side view in elevation 20 of the pole of Fig. 10.

Fig. 12 is a side elevational view of one form of my new cylindrical structure, being a pole, wherein some of the longitudinal 25 structural members extend for the entire length of the structure, while the remainder of the longitudinals extend for only about three-fourths of the length of the structure.

Fig. 13 is a side elevational view of a form 30 of my new cylindrical structure, with part broken away to show added strengthening or stiffening means inserted or applied at desired intervals.

Fig. 14 is a cross-sectional view of a form 35 of the new cylindrical structure, in which additional strength or stiffness is given by the employment of tying loops, or the like, for connecting oppositely-disposed longitudinals of the circular or other group thereof.

40 Referring to Figs. 1-7, A indicates a mandrel having grooves A¹ extending longitudinally thereof. The mandrel may have a length equaling that of the entire pole or post, or equaling that of the section of the structure to be made. As more particularly described hereinafter, such mandrel may be a pole-piece of an electromagnet (or a continuation thereof).

B indicates longitudinal structural members, here shown as V-shaped angles, laid in the grooves A¹ of the mandrel, and held in place by any means, such as the magnetic attraction of the mandrel. The outer edges of the flanges receive the next-hereinafter described rods, or bars, when helically wound around the assembled group of longitudinals.

C¹ indicates rods or bars woven around said group of longitudinals in a desired direction (for instance, clockwise), and C¹¹ 60 indicates other rods or bars woven around the group of longitudinals in an opposite direction. Preferably, the weaving is uniform, with opposite spirals crossing each other in 65 pairs at their intersection with a longitudi-

nal member and at this junction the three are secured together being preferably electrical-ly forged or welded.

C, C¹⁰ indicate weaving heads which may be employed to lay the rods or bars helically and lengthwise of the longitudinals. 70

D and D¹ indicate welding apparatus, for securing the rods, or bars, and the longitudinals together.

The longitudinals, and also the helices 75 wound thereover, may be held in place by the attractive action of the magnet which has a mandrel formed or connected to act as a pole-piece, awaiting the operation of welding. 80

The structure, formed in the manner de-scribed, generally is an integral net-work of trussed longitudinal structural members. Such trussed construction gives the unit structure great stiffness and strength by permitting the longitudinal members to act under strain as compression struts. The longitudinals are so invested by virtue of their being supported, at predetermined points, both diagonally and circumferentially, 90 against deflection by the helically-arranged diagonal rods or bars.

Applied to the construction of a pole, the longitudinal members carry the direct compression or tensile stresses, while the helically-arranged rods (or bars) act as bracing 95 means for limiting the unsupported lengths of the compression members, and for resisting torsion or twisting.

A pole or post made of this construction 100 has equal strength in all directions and has a high torsional resisting strength. Being made of a multiple number of struts, it is not subject to sudden collapse under failure; the longitudinal members being at different dis-tances from the neutral axis (of the circular 105 or other cross-section) do not fail in unison, the loads they carry being in proportion to their distance from the before-mentioned neutral axis. With the collapse of the outer-most member, the inner members must first take up the additional burden before they, 110 in turn, fail.

With these inherent qualities, the struc-ture surpasses the ideal tube as a means of 115 carrying loads by beam or cantilever action; its superiority lies in the fact that a better distribution of steel is possible, and with the same amount of steel a higher resisting moment is obtained.

A pole constructed in accordance with the present invention is light in weight, being lighter than a wooden pole of like cross-section and length, and is much stronger than such a wooden pole. 120

It is possible to make a structure or pole having a greater transverse strength by substituting heavier structural shapes in the sides where the greater strength is required.

The longitudinal members are of any kind 130

or shape, though for general utility, the angle is preferred. The helically-disposed members may be of any shape or form but are preferably of rectangular or circular section. The principal of the construction is applicable to any form or shape of longitudinals, this being true also of the helically-disposed members. Preferably, the longitudinals and also the helical members are of steel.

The structure is equally applicable to any rectangular, triangular, cylindrical, tapered, conical or other form.

The helix or the helices may be woven around the group of longitudinals, or may, as hereinafter described, be on the inside of the group, or be both inside and outside of the group.

The structure lends itself to the simplest kind of mechanical fabrication. For instance, as illustrated in Figs. 1-6, the structural longitudinals may be laid in the grooves of a mandrel a weaving mechanism (consisting of two heads) lays the helices, while a welding head may make eight, or any multiple of circumferential welds in one operation.

The helices can, obviously, be "wound-on" in single rods or multiples from one or more spools disposed lengthwise or alongside of the mandrel.

An entire pole may be made in one continuous operation upon the same mandrel, or, the assemblage may be limited to only a section of a pole.

The sections can be nested for shipment, and afterwards assembled by joining them end to end, somewhat after the fashion of assembling stove pipes. One form of complete pole is shown in Figure 7 of the accompanying drawings.

The structure when made into a pole may be reinforced, by rings, F, F¹, F² and F³, as shown, at a point below the ground line, at the butt, at the top, and at intervals throughout the length of the pole. Some of the bands or rings, F¹ and F², may also be used to secure the sections of the pole together. The said bands or rings, especially when attached at the junction with longitudinal and helical members, act to reduce the unsupported lengths of the longitudinals and take circumferential stresses; they thus act as stiffening and strengthening means.

Referring, now, to Figures 8-11 of the accompanying drawings, these illustrate manners of assembling elements of a pole, or other structure, with the helically-disposed rods, or bars, inside of the group of longitudinals.

In the case of Figures 8 and 9, oppositely-woven rods, C⁹⁸ and C⁹⁹, are shown as wound around a mandrel, A², and longitudinals, B³, positioned about the rods. In the case of

Figures 10 and 11, oppositely-woven rods, indicated as C¹⁰⁰ and C¹⁰¹, are shown as wound

around the longitudinals which latter have helically-disposed rods within the group of longitudinals.

For the sake of lightness, and also since, for many purposes, the upper end of a pole need not be as strong as the lower end thereof, some of the longitudinals need not extend to the upper end of the pole, it being sufficient if (say) one-half of the longitudinals shall reach to the uppermost end of the pole. Such a structure, made in accordance with my invention, is illustrated in Fig. 12, in which B⁹⁹ indicates the longitudinals which extend for about three-quarters of the length of the pole, while the other longitudinals, indicated at B¹⁰⁰, run from end to end of the structure.

In this case, as in Fig. 7, strengthening or stiffening rings, F¹, F² and F³ are shown as surrounding the pole.

Instead of being external of the structure, strengthening or stiffening diaphragms, disks or plates, indicated at G and G¹, may be placed within the pole as shown in Figure 13.

Referring to Figure 14, I may use tying means instead of the rings or the internal diaphragms, disks or plates, for maintaining the relative position of the longitudinals, and thus stiffening and strengthening the pole. The object sought will be accomplished, in the case of Figure 14, by using as many ties, E, as there are pairs of longitudinals, and employing each tie to engage with and pass around oppositely arranged longitudinals.

It will be observed with reference to Fig. 7 that a pole constructed in accordance with the present invention is of the same lattice work structure throughout including the portion embedded in the earth as shown at X. The fact that a special base for embedding the lower end of the pole in the earth is not required with the pole disclosed herein, represents an economy of construction, but further and more important than this element is the fact that due to the use of the lattice work construction underground, the earth becomes tightly packed about all sides of the members as well as into the angles of the longitudinals and thus grips the pole so firmly that it offers a greater resistance against movement than a solid or tubular pole of the same external dimensions.

In the appended claims the structure disclosed herein is described as comprising rods wound in left and right hand helices, etc. The term "helices" as used in the claims is intended to include a true helix of constant generating radius throughout its entire extent, as well as a tapered helix wherein the generating radius of the helix decreases gradually from one end to the other of the structure.

What I claim is:

1. A latticed metal pole or column com-

prising rods wound in left and right hand helices together with stiffened bars extending longitudinally in contact with said rods and welded thereto at the contact points.

5 2. A latticed metal pole or column comprising rods wound in left and right hand helices together with flanged bars extending in alignment with the intersections of said rods and welded thereto at said intersections.

10 3. A latticed metal pole or column comprising rods wound in left and right hand intersecting helices having substantially equal pitch, and flanged bars extending in alignment with the intersections of said rods and

15 welded thereto at said intersections.

4. A latticed metal pole or column comprising rods wound in left and right hand intersecting helices together with flanged bars of angle section extending in alignment with

20 the intersections of the said rods and welded thereto at said intersections, said angle bars being positioned about said helically wound rods with their vertices pointing outwardly,

25 whereby said pole provides great resistance against movement with a portion thereof implanted in the ground.

5. A latticed metal pole or column comprising rods extending in right and left hand intersecting helices together with flanged bars

30 extending in alignment with the intersections of said rods and welded thereto at said intersections, said rods being shaped to follow substantially straight line paths between adjacent bars.

35 Signed at New York in the county of New York and State of New York this 27th day of September, A. D. 1928.

VICTOR F. HAMMEL.
